UNITED STATES PATENT OFFICE.

ABBOT AUGUSTUS LOW, OF BROOKLYN, NEW YORK, ASSIGNOR TO THE ALDEN TYPE MACHINE COMPANY, OF NEW YORK, N. Y.

TYPE-DISTRIBUTING APPARATUS.

SPECIFICATION forming part of Letters Patent No. 668,814, dated February 19, 1901.

Application filed July 7, 1900. Serial No. 22,778. (No model.)

To all whom it may concern:

Be it known that I, ABBOT AUGUSTUS LOW, a citizen of the United States, residing in the city of New York, borough of Brooklyn, in the county of Kings and State of New York, have invented certain new and useful Improvements in Type-Distributing Apparatus, of which the following is a specification sufficient to enable others skilled in the art to 10 which the invention appertains to make and use the same.

My improvements relate to mechanism for transferring types from one channel to another, and are designed more particularly for 15 use in automatic type-distributing apparatus of the class known as the "Alden distributor."

The object of my invention is to dispense with the comparatively-complicated mechanism heretofore in use for this purpose and to render the apparatus much more simple and effective in construction and operation, at the same time materially lessening the cost of construction and maintenance.

25 My present invention is essentially an improvement or modification of the structure disclosed in my Patent No. 650,405, dated May 29, 1900, in which the types are forwarded from a channel in which they are deposited in the same relation to each other in which they come from the press by means of a reciprocating type-pusher onto a lifter, by which they are transferred to and beyond the latch mechanism at the lower ends of type-containing channels desired for the particular letters forwarded.

In my previous patent above referred to the individual channel or channels for receiving the individual types from the lifters are 40 inclined toward the galley-channel and a straight grooved lifter is utilized in transferring the type from the galley-channel to each individual channel.

The invention consists in the special construction of the lifters as herein described and claimed for the purpose of adapting them to the requirements of a machine in which the individual channels are arranged vertically.

50 In the accompanying drawings I show only sufficient of the apparatus to illustrate my

present invention, the other parts of the apparatus being of the well-known form of construction and the operating and signaling apparatus, &c., being substantially the same as 55 heretofore, as will be fully understood by reference to Patent No. 212,503, issued to A. C. Richards February 18, 1879, and No. 245,562, issued to T. Reeve August 9, 1881.

Figure 1 is a sectional elevation through 60 the channel and adjoining parts, showing the lifter in its normal position, a type having just been forwarded thereon by the horizontal pusher, which has been again retracted. Fig. 2 is a similar view showing the lifter 65 raised by the actuating-ring. Figs. 3 and 4 are respectively side and top views of my improved lifter.

A represents the channel into which the lines of type from the galley are introduced. 70 The column of type in each channel A rests upon the floor a, over which the pusher P is made to reciprocate by suitable mechanism, thereby forwarding the lowest type in a column onto the lifter L, by which the type is 75 raised into the individual channel I to be supported upon the latches i. The lifters L are actuated by the ring R precisely in the manner set forth in the patents hereinbefore referred to. The upper side of the lifters L is 80 formed with two type-receiving surfaces l l', which are at an angle to each other, the first surface l being coincident with and forming a continuation of the type-floor a when the lifter L is at rest in its normal position—that 85 is, in its lowest position. The other type-receiving surface l' is formed at such an angle that when the lifter is raised said surface l' will extend transversely across the individual channel I and at right angles to the spine 90 thereof, as shown in Fig. 2, so as to raise the lowest type squarely and evenly above the latches i.

The primary receiving-surface l on the lifter L is flanked by retaining walls or shoulders l'', as in my patent hereinbefore referred to. This preliminary surface l is preferably slotted, as shown in the drawings, so that it consists practically of opposed shoulders which support the opposite edges of the type. 95

The sides of the lifter L are formed with recesses l'', which coincide with the latches i

in the sides of the individual channel I, so as not to interfere therewith when the lifter is raised.

The construction of the latches *i* is the same as in the Alden distributor, and I do not claim novelty in this respect. Neither do I claim any novelty in the operation of the lifter L, the mechanism for actuating the lifters being clearly in the state of the art. The novelty in the construction of the lifter consists in the specific construction and arrangement of parts hereinafter claimed, whereby the types may be transferred from the vertical galley-channel A to the vertical individual channel I.

Heretofore the types have been picked up, manipulated, and transferred by delicate and complicated mechanism which has not always been positive or accurate in operation, whereas by my improvements I not only dispense with the complication of parts, but also insure a direct and positive delivery of the types, which are not turned or deviated from the direct line of advance during the operation of transferring them from one channel to another.

What I claim as my invention, and desire to secure by Letters Patent, is—

1. In a type-distributing apparatus of the class herein designated, the combination of the vertical type-receiving channel A, the horizontal type-floor *a*, the reciprocating type-pusher P, the lifter L, formed with the type-floors *l*, *l'*, inclined with relation to each other, the individual channel I, and the latches *i*, *i*, the whole arranged and operating substantially as herein described.

2. In type-distributing apparatus of the class herein designated, the combination of the vertical type-receiving channel A, the horizontal type-floor *a*, the reciprocating type-pusher P, the lifter L, formed with the type-floors *l*, *l'*, inclined with relation to each other, and with the lateral recesses *l*³, the individual type-channel I, and the latches *i*, *i*, the whole arranged and operating substantially as herein described.

ABBOT AUGUSTUS LOW.
